CHRISTMAS TREE STAND

Michael Cosentino, Chicago, Ill., assignor to Modern Coatings, Inc., Chicago, Ill., a corporation of Illinois

Application May 22, 1959, Serial No. 56,024

Term of patent 14 years

(Cl. D35—3)

Fig. 1 is a perspective view of a Christmas tree stand embodying my new design, the stippled shading representing a contrasting material;

Fig. 2 is a side elevational view of the same on a reduced scale; and

Fig. 3 is a top plan view of the same on a reduced scale.

I claim:

The ornamental design for a Christmas tree stand, substantially as shown and described.
